UNITED STATES PATENT OFFICE.

GREENLEAF STACKPOLE, OF NEW YORK, N. Y., ASSIGNOR TO HIMSELF AND
H. C. COVERT, OF SAME PLACE.

IMPROVED MACHINE FOR SEWING BROOMS.

Specification forming part of Letters Patent No. 91,784, dated June 22, 1869.

To all whom it may concern:

Be it known that I, GREENLEAF STACKPOLE, of New York city, in the county and State of New York, have invented a new and valuable Machine for Sewing Brooms.

The nature of my invention consists in providing mechanism for sewing brooms.

The object of my invention is to reduce the labor of making brooms to the lowest practicable point by constructing and providing manufacturers with a machine which will perform the greater portion of the work—viz., the sewing, pressing, and binding in a better manner and in less than one-tenth the time that has hitherto been required to perform the same operation by hand.

Having thus given the object of my invention, I do hereby declare that the following is a full, clear, and exact description of the construction and operation of the same, reference being had to the annexed drawings, making a part of this specification, in which corresponding letters represent corresponding parts.

Figure 1 is a top view of my invention, in which A is the needle-bar and a the needle; B, the shuttle, and b the slack-thread controller. C C are the jaws of the press, and D is the handle of the same, which operates an eccentric held by the clamp d, for the purpose of closing or opening the jaws. E is the shuttle-driver, and F a covering for the shuttle, which is thrown back in order to show the shuttle and driver. The dotted red line G shows the direction of the binding-twine. The red line H shows the thread which is carried by the needle. h is the spool, which holds the thread for the needle. The black dotted line I shows the position of the spool that holds the binding-twine.

Fig. 2 is a side elevation of my machine, in which K is the lever which connects the needle-bar A with the driving-cam L; M, the arm which drives the shuttle, and N the cam which gives the alternate upward and downward motion to the pressing-jaws C C, necessary to force the needle through the broom above and below the binding-twine. O is the crank which drives the shuttle-arm M, and

P a wire with an eye, R, in its upper end to guide the binding-twine relatively to the point of the needle, as may be desired in making the different stitches. The dotted red lines show the position of the broom while being bound and sewed, it being held in the press with its edge toward the operator, and handle upward.

Fig. 3 is an end elevation of my machine. S is a cam-slot, in which the crank-pin O plays, and which drives the shuttle-arm. T is a portion of the lower part of the press, having ratchet-teeth cut thereon. U is the pawl that plays into the ratchet, and is operated by the lever shown by the dotted lines, said lever being put in motion by the cam W.

Fig. 4 represents the shuttle, the red lines showing the direction of the thread. The tension is obtained by passing the thread around the grooved wheel Y in the back end of the shuttle, said grooved wheel being made to work easier or harder by turning the screw X, which draws a padded surface against it. One end of the bobbin is held in the end of the shaft, upon which the grooved wheel Y turns, the opposite end dropping into a groove, and being held in place by a guard in such manner as to allow it to run free, no tension whatever being given to the bobbin.

Fig. 5 represents a broom, showing the work made by this machine, the different appearance of the stitches being produced by the changing of the motion of the feed-press by means of a connection with the cam N and slide Z, that passes and returns alternately between the ratchet-teeth T and the pawl U in such manner as to stop the feeding connection, taking one stitch above and another below the line. Before feeding along a variety of fancy stitches may be made in this way. My machine makes those shown in the drawings.

Instead of the pressing-jaws C C being made to rise and fall, the needle-bar and shuttle could be made so as to produce the motion necessary to carry the thread across the binding-twine, and I have previously constructed a machine in that way, but prefer the arrangement shown in the accompanying drawings.

Having thus described my invention, what I

claim as new, and desire to secure by Letters Patent, is—

1. The pressing-jaws C C, in combination with the shuttle B and needle *a*, for sewing brooms, substantially as set forth.

2. The arrangement of the pressing-jaws C C, in such manner that each revolution of the cam N or its equivalent will cause them to

rise and fall alternately with the motion of the needle and the shuttle, substantially as and for the purpose set forth.

GREENLEAF STACKPOLE.
